UNITED STATES PATENT OFFICE.

SAMUEL HOFFMAN, JOSEPH SCHWARTZ, AND ISIDORE HOLDEN, OF NEW YORK, N. Y.

DRAWING INSTRUMENT.

1,406,863.

Specification of Letters Patent. Patented Feb. 14, 1922.

Application filed March 28, 1921. Serial No. 456,393.

To all whom it may concern:

Be it known that we, SAMUEL HOFFMAN, JOSEPH SCHWARTZ, and ISIDORE HOLDEN, all citizens of the United States, and residents 5 of the city of New York, borough of The Bronx, in the county of Bronx and State of New York, have invented a new and useful Drawing Instrument, of which the following is a full, clear, and exact description.

10 This invention relates to drawing instruments, and particularly to what is commonly known as an ellipsograph, and has for an object to provide a construction wherein by a quick adjustment different 15 forms of ellipses may be drawn.

Another object of the invention is to provide an ellipsograph wherein a quick adjustment may be provided which will cause a variation in the length of the minor 20 axis without affecting the length of the major axis.

Another object, more specifically, is the provision of an ellipsograph formed on the general principles of a compass with an adjustable guide arranged to guide the scrib- 25 ing member for producing ellipses of different sizes and shapes.

In the accompanying drawing—

Figure 1 is a longitudinal vertical section through an ellipsograph embodying the invention, the same being taken approximately on line 1—1 of Fig. 2.

Figure 2 is a top plan view of the ellipsograph shown in Figure 1.

Figure 3 is a view similar to Figure 1, but showing the instrument adjusted for producing an ellipse having a different minor axis from the ellipse produced by the arrangement of parts shown in Figure 1.

Figure 4 is a top plan view of the ellipsograph shown in Figure 3.

Referring to the accompanying drawing by numerals, 1 indicates a base plate, preferably provided with a centering spur 2 and rigidly connected with uprights 3 and 4, which preferably merge into a body 5 having a longitudinal slot 6. Body 5 merges into a round extension 7 having a pin 8 on which a rotatable sleeve 9 is mounted, said 50 sleeve having an arm 10 slidably fitting into a tubular member 11 rigidly secured to a vertically positioned bar 12 provided with graduations 13. A spring 14 is connected with bar 12 near the sleeve or tubular member 11 to the rounded extension 7

so as to cause the tubular member 11 and bar 12 to normally have a tendency to move toward the rounded extension 7. This continuous tendency will cause the bar 12 to continually bear against the guide ring 60 14. A link 15 is pivotally connected to bar 12 at 16, said link carrying a hollow reduced extension 17 surrounded by a spring 18 which bears against a clamping screw 19 and against the shoulder 20. The reduced extension 17 is slidably mounted in a bore 21 in link 15 so that the spring 18 will continually tend to hold the lead or other marking member 22 against the surface to be marked, said lead being rigidly 70 clamped in member 17 by the screw 19.

As shown in Figure 2 the guiding ring 14 is formed as a circular member and when arranged at right angles to the body 5, as shown in Figure 1, causes the marking 75 member 22 to produce a true circle. If it should be desired to make this circle slightly elliptical the ring 14 is tilted slightly. In case an ellipse having a much longer major axis than a minor axis is desired, the ring 80 14 is tilted at an appreciable angle as shown in Figures 3 and 4. In order to guide, or rather in order to assist in determining the amount of tilting of the ring 14 graduations 13 are provided on bar 12 and the 85 upper edge of the ring 14 is caused to register with any of the marks on this graduation according to the particular ellipse desired. In order to allow for this movement the ring 14 is provided with a central 90 bar 24 to which it is rigidly secured, said bar being formed of T-shaped material as shown in Figure 1, and the set screws 25 and 26 extend through part of the frame 5 and into the grooves of bar 24 95 so as to clamp the bar in whatever position desired, as for instance, the position shown in Figure 3. It will be noted that the major axis of an ellipse cannot be varied but the minor axis may be changed 100 readily as may be desired.

In case the two ellipses are made close together and of the same size, spur 2 may be located properly for the first ellipse and then the screws 25 and 26 loosened slightly 105 to allow the ring 14 to be moved in a direction longitudinally of the bar 24. Where this movement is very small, as for instance, a sixteenth or eighth of an inch the second ellipse will be properly positioned to co-act 110

with the first ellipse though if the second ellipse is to be made an appreciable distance from the first, it is preferable to move the entire instrument over to the major axis of the second ellipse.

What we claim is:—

1. An ellipsograph comprising a standard, a scribing member carried by the standard adapted to move around the standard, a ring for guiding said scribing member, a bar rigidly connected with the ring and slidably fitted in said standard, and a pair of clamping screws for clamping the bar in different positions whereby when 15 said bar is moved longitudinally and bolted so that more of the ring will be on one side of the standard than the other and when the major portion of the ring is inclined downwardly a substantially true ellipse will be 20 produced with the minor axis in proportion

to the angle of said bar and the position thereof in respect to the standard.

2. An ellipsograph comprising a standard, a scribing instrument connected with the standard and adapted to move around the standard, the scribing instrument provided with a series of graduations, a ring carried by the standard, and means for adjustably clamping the ring to the standard so that the ring may be tilted from a horizontal 25 and moved more on one side of the standard than the other, said tilting movement being determined by the graduations on said scribing instrument, said graduations determining the size of the major axis of the 30 ellipse to be moved.

SAMUEL HOFFMAN,
JOSEPH SCHWARTZ.
ISIDORE HOLDEN.
